LUGGAGE CASE

Josef A. Ross, 24 Sergent Court,
Bergenfield, N.J. 07621

Filed Mar. 2, 1970, Ser. No. 21,697

Term of patent 14 years

Int. Cl. D3—01

U.S. Cl. D87—5

FIG. 1.

FIG. 2.

FIG. 3.

FIG. 4.

FIG. 1 is a front elevational view of a luggage case, showing my new design, the other side being similar in appearance;

FIG. 2 is a top view thereof;

FIG. 3 is an end view thereof, the other end being similar in appearance; and

FIG. 4 is a bottom view thereof.

I claim:

The ornamental design for a luggage case, substantially as shown and described.
